ELECTRIC HANSAW

Filed Oct. 24, 1924

2 Sheets-Sheet 2

Fig. 3.

This cross-sectional diagram illustrates a complex mechanical assembly, possibly a gear train or a transmission. The components are labeled with numbers:

- Outer housing: 43
- Shaft: 39
- Shaft: 38
- Shaft: 18
- Shaft: 21
- Shaft: 61
- Shaft: 41
- Shaft: 29
- Shaft: 42
- Shaft: 20
- Shaft: 6
- Shaft: 5
- Shaft: 48, 49
- Shaft: 45
- Shaft: 46
- Shaft: 59
- Shaft: 60
- Shaft: 54
- Shaft: 17
- Shaft: 53
- Shaft: 64
- Shaft: 63
- Shaft: 19
- Shaft: 64
- Shaft: 63
- Shaft: 13
- Shaft: 68
- Shaft: 16
- Shaft: 14
- Shaft: 11

The assembly features a central gear train with multiple gears (54, 59, 60, 53) and shafts (17, 19, 13) supported by bearings and housed within a multi-layered outer housing (43). Various shafts (39, 38, 18, 21, 61, 41, 29, 42, 20) are shown extending from the housing, some with associated components like 48, 49, 45, 46, 64, 63, 68, 16, 14, and 11.

UNITED STATES PATENT OFFICE.

WILLIAM P. CASEY, OF OSHKOSH, WISCONSIN.

ELECTRIC HANDSAW.

Application filed October 24, 1924. Serial No. 745,634.

This invention relates to certain new and useful improvements in electric hand saws of that type which is readily portable and preferably capable of general use in the wood working and kindred arts.

It is one of the objects of this invention to provide a compact, unitary, well-balanced electric hand saw with which different types of cutters may be employed to be adapted for various types of work.

In electric hand saws of that type illustrated in Letters Patent No. 1,497,067, granted me the 10th day of June, 1924, the gear housing and motor are arranged end to end. This arrangement produces a very satisfactory tool, although it is somewhat unsatisfactory for certain types of work by reason of its overall length and this invention has as another object the provision of a tool of the character described of decreased overall length.

Another object of this invention resides in the provision of a tool of the character described in which the tool adjusting member works on an axis arranged at substantially right angles to the axis of the drive motor.

A further object of this invention resides in the provision of a tool of the character described in which the gear housing and motor are disposed at right angles with their axes intersecting the motor shaft extending into the gear housing for a drive connection with the tool arbor.

And a still further object of this invention resides in the provision of an improved tool of the character described in which the gear housing is rotatably mounted at either end and provided with an intermediate brace carried by the drive motor and, if desired, providing means for closing the elongated opening through which the motor shaft projects into the gear housing.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the

physical embodiment of my invention constructed according to the best mode I have so far devised for the practical application of the principles thereof, and in which:

Figure 1 is a top plan view of a tool embodying my invention, parts thereof being broken away and in section to more clearly illustrate details of construction; 60

Figure 2 is a view, partly in transverse section and partly in elevation, taken 65 through Figure 1 on the plane of the line 2-2, and

Figure 3 is a view, partly in section and partly in elevation, taken through Figure 1 on the plane of the line 3-3. 70

Referring now more particularly to the accompanying drawings, in which like numerals designate like parts throughout the several views; the numeral 5 designates a base member of substantially rectangular 75 form and having its under-face or surface 6 trued for engagement with the work, the work engaging surface being provided with a slot 7 to receive a suitable mitre attachment, not shown.

Mounted adjacent one side of the base member is an elongated handle 8 which is secured between a pair of upstanding members 9 and 10 carried by the base at its ends, the member 10 having provision for mounting a switch 11 included in the feed wires 12 of the drive motor 13. A shorter handle 14 is mounted adjacent the opposite side of the base member, substantially parallel to the handle 8, and is confined between two upstanding members 15 and 16. The member 15 is carried by the end of the frame opposite member 9 and member 16 is positioned adjacent the side of the frame but medially of the ends. 80

The motor 13 is suitably mounted on the base member between the handles 8 and 14 with its inner end terminating approximately on a plane with the member 16, the drive shaft 17 of the motor being extended therebeyond into a gear housing 18 through an elongated slot or opening 19 in the side wall thereof. The gear housing 18 is mounted on that portion of the base member between the handle member 16 and the base member end 20 and is preferably formed with one end permanently closed by a wall 21 and its other end closed by a removable end wall or cover 22 which is secured in position by cap screws or other means 23. 100

A center recess or pivot opening 24 is formed in the outer face of the end wall 21 to receive the inner pointed end 25 of an adjustable pivot 26 which is threaded through 5 the lower end 27 of a suspension strap 28 carried by a standard 29. The standard 29 is mounted on the base member adjacent its outer edge 30 by suitable fastening means 31 and has a horizontal bore 32 in which the 10 adjacent end of the gear housing freely rotatably fits.

The end wall 22 is provided with a journal or boss 33 which is in axial alignment with the center recess 24 and is journaled in a 15 bearing 34 formed in the upper end of a standard 35 carried by the base member. The bearing 34 is in axial alignment with the pivot 26 and the gear housing is held against longitudinal movement by the adjustable 20 pivot 26 and a shoulder 36 formed at the inner portion of the journal 33 and engaging against the bearing 34. Lost motion or slack is taken up by the adjustable pivot 26 which is readily releasably secured in 25 adjusted position by a lock nut 37.

The gear housing 18, as above described, is mounted for rotation, but is firmly held against vibration and may be secured in any position of adjustment by a binding nut 38 30 threaded on a screw 39 carried by the gear housing and passed through an elongated slot 40 in a strap 41. The strap 41 is slightly spaced inwardly of the standard 29 and is secured in position by suitable fastening 35 members 42. When the binding nut 38 is freed of strap 41, the gear housing may be freely rotated within the limits of the slot by a handle member 43 provided for this 40 purpose and when the gear housing has been rotated the desired degree, it is firmly secured against rotation by bringing binding nut 38 into firm engagement with the strap member.

The degree of rotation of the gear housing may be regulated by a depth or adjusting 45 ring 44 rotatably mounted on the gear housing between the strap member 41 and the standard 29. Ring 44 is securable to the gear housing against rotation by a friction 50 screw 45, the inner end of which is adapted to force a plate or shoe 46 into engagement with the gear housing. Formed on the ring 44 adjacent the friction screw 45 is a projection 47 in the path of which lies a lug 48 55 carried by the strap 41. When it is desired to rotate the gear member a predetermined degree from its position, the friction screw 45 is loosened to free the ring of the gear housing and the gear housing then rotated 60 to space the lugs 47 and 48 the desired distance. The ring 44 is then made fast to the gear housing by means of the friction screw 45, the binding nut 38 loosened and the gear housing rotated by means of the handle 65 member 43 to reengage the lugs 47 and 48

when the binding nut 38 is again made fast to secure the gear housing against further rotation.

Journaled in the gear housing to one side of its center by bearings 49 and 50 and having its end 51 extended outwardly thereof beyond the side 30 of the base member, is a tool arbor 52, on which is medially secured a pinion gear 53. The gear 53 meshes with an intermediate or idle gear 54 suitably 75 mounted in the gear housing and meshing with a pinion gear 55 journaled on a stub shaft 56 fixed in a boss 57 extended from the gear housing wall 21. The gear 55 rotates on the axis of the gear housing and 80 has a sleeve or bushing 58 extended therefrom on which is splined or otherwise fixed a bevel gear 59 with which meshes a bevel gear 60 fixed in the end of the motor shaft 17 extending into the gear housing. The 85 gears 59 and 55 rotating on the axis of the gear housing 18 permits its rotation to adjust the position of the tool arbor with respect to the work engaging face of the base member without in any manner disturbing 90 the drive between the gears 59 and 60.

As before described, the motor shaft 17 passes into the gear housing through an elongated slot or opening 19 and in order to prevent the entrance of shavings or other 95 foreign matter into the housing to thus protect the housing, I provide a ring 61 which surrounds the housing at the opening 16 and has an opening 62 therein through which the shaft 17 passes, the ring 61 remaining stationary at all times, as will be readily apparent. As best illustrated in Figure 3, ring 61 is provided with oppositely extending lugs 63 through which securing means 64 pass to firmly connect the same with the 100 motor housing whereby an intermediate journal support or brace is provided for the gear housing to thus further strengthen the 105 same and eliminate vibration.

A saw or other cutter 65 is secured to the 110 extended end 51 of the tool arbor and a guard 66 is provided therefor which is suitably fixed on a boss 67 surrounding the point at which the tool arbor passes outwardly of the gear housing.

From the foregoing description taken in connection with the accompanying drawings, it will be readily obvious to those skilled in the art to which an invention of this character appertains that I provide a 120 well balanced and efficient portable saw in which the overall length has been reduced and one which may be used in connection with various types of work and which will permit fast and efficient work.

What I claim as my invention is:

1. In a tool of the character described, a base member, a housing member, means rotatably mounting the housing member on the base member, a tool arbor journaled in 130

the housing member to one side of its axis and having its end extended outwardly thereof to receive a cutting tool, a drive motor mounted on the base member with its axis at an angle of ninety degrees with respect to the axis of the housing member, a band medially surrounding the housing member, means securing said band to the motor housing, a motor shaft passed into the housing member and a drive connection between the motor shaft and tool arbor.

2. In a tool of the character described, a base member, a vertical standard mounted on the base member and provided with a horizontal bearing, a suspension strap carried by said standard with its inner end in

register with the axis of the bore therein, a second standard carried by the base member, a bearing in the upper end of said second standard with its axis in alignment with the axis of the bore of the first standard, a housing member having one end rotatable in the bore of the first standard, a journal on the other end of the housing member and rotatable in the second standard bearing, a pivot member carried by the inner end of the suspension strap pivotally engaging the adjacent end of the housing member, and means for securing the gear housing against rotation.

In testimony whereof I affix my signature.

WILLIAM P. CASEY.
